UNITED STATES PATENT OFFICE.

HENRY J. BRODERSON, OF WHITING, INDIANA, ASSIGNOR TO STANDARD OIL COMPANY, OF WHITING, INDIANA, A CORPORATION OF INDIANA.

REFINING HYDROCARBON OILS.

Application filed June 7, 1924. Serial No. 718,574.

The present invention relates to improvements in the refining of hydrocarbon oils, and more particularly of the lighter distillate oils, such as naphthas, pressure still distillates, burning oils and the like. It will be fully understood from the following description illustrated by the accompanying drawings, in which apparatus suitable for carrying the invention into effect is shown diagrammatically, and partly in section.

Referring more particularly to the drawing, the numeral 5 indicates a receptacle having a conical bottom provided with a drain pipe 6. This receptacle is of the usual form employed in refineries for treating purposes, for example, as agitators.

The oil to be treated, which may be, for example, pressure still distillate, is pumped or forced by any suitable means from a source of supply through the supply pipe 7 into and through the preheater 8. From the preheater 8, the oil passes into a suitable mixing device, for example, the baffle mixer 9, in which it is thoroughly mixed with treating liquid, as hereinafter set forth. From the mixer 9 the oil, admixed with treating liquid, passes through pipe 10 into a discharge pipe 11, by which it is discharged into the receptacle 5. The discharge pipe 11 has a closed end and extends nearly to the bottom of the receptacle, being provided near its lower end with perforations 12, through which the mixture of oil and treating liquid enters the receptacle 5. In the receptacle 5 the oil and treating liquid separates, the treating liquid settling to the bottom and sufficient thereof being maintained in the receptacle to keep its level above the perforations 12 in the discharge pipe 11, for example, as indicated at 13. The separated oil overflows from the receptacle 5 through the overflow pipe 14. Separated treating liquid is withdrawn from the bottom of the receptacle 5 through the drain pipe 6 by the pump 15, which forces it through the pipe 16 into the mixer 9 in proximity to the point of entrance of the oil.

The process of the present invention may advantageously be employed in the treatment of distillates with "doctor" or sodium plumbite solution as ordinarily employed in refinery practice. In beginning operations, a sufficiently large amount of the doctor solution is placed in the agitator 5. Oil is

forced from the source of supply to the pipe 7, and the preheater 8 into the mixer 9, the pump 15 being simultaneously operated to force in a suitable proportion of doctor solution withdrawn from the bottom of the agitator or receptacle 5. This proportion may suitably be from 5 to 10% of the oil in volume. The oil, in passing through the preheater 8, may suitably be brought to a temperature of 80 to 100° F. In passing through the mixer 9 the oil and doctor solution are thoroughly mixed, and together pass through the pipe 10 into the pipe 11, which leads the admixed oil and doctor solution into the agitator 5 and discharges them through the perforations 12 into the body of separated doctor solution therein, the latter being suitably maintained at the level 13. In passing through the body of doctor solution there is a further washing or treating action of the doctor solution upon the oil. The oil separates from the doctor solution, the latter descending into the lower portion of the agitator while oil overflows through the overflow pipe 14. An extremely rapid and efficient treating of the oil is thereby effected.

If desired, the preheater 8 may be eliminated from the system, and with certain distillates, such as straight run naphtha, and the like, in general the use of a preheater is not necessary. It is found preferable, however, to control the preheater to secure a desired oil temperature of, suitably, from 80 to 100° F., the optimum conditions for any specific distillate to be treated being readily determined by experiment.

I claim:

1. The method of refining hydrocarbon oil distillates in continuous flow which comprises heating a flowing stream of such distillate to a temperature of 80 to 100° F., maintaining a body of treating reagent, withdrawing treating reagent continuously from said body of treating reagent and admixing it with the flowing stream of heated oil, conducting the stream of oil and admixed reagent into the body of liquid treating reagent below its surface, whereby the oil is forced to travel through the body of treating reagent, permitting separation of the oil above the body of treating reagent and continuously withdrawing separated oil.

2. The method of sweetening hydrocarbon oil distillate in continuous flow which com-

prises heating a flowing stream of such distillate to a temperature of 80 to 100° F., maintaining a body of doctor solution, withdrawing doctor solution continuously from 5 said body of doctor solution and admixing it with the flowing stream of heated oil, conducting the stream of oil and admixed doctor solution into the body of doctor solution below its surface, whereby the oil is forced 10 to travel through the body of doctor solution, permitting separation of the oil above the body of doctor solution, and continuously withdrawing separated oil.

3. An apparatus for treating hydrocarbon 15 oil distillates with "doctor" comprising a receptacle, an eduction pipe leading from the bottom thereof and adapted to withdraw "doctor" therefrom, a pump in said eduction pipe, oil supply means communicating 20 with said eduction pipe, heating means adapted to receive oil and "doctor" solution from said eduction pipe and oil supply means and heat same, a mixer communicat-

ing with said heating means, conduit means leading from said mixer to the lower portion of said receptacle, means for subdividing the incoming liquid from said conduit and means for withdrawing oil from said receptacle at an elevated part thereof. 25

4. In apparatus for treating hydrocarbon 30 oil distillates, a receptacle adapted to contain a body of a liquid treating reagent, a heating device, a mixing device, means for forcing oil through the heating device into the mixing device, means for withdrawing 35 treating reagent from the bottom of said receptacle and forcing it into the mixing device in proximity to the point of entrance of the oil, means for withdrawing mixed oil and treating reagent from the mixing device 40 and forcing it in finely divided condition into the lower portion of the receptacle, and means for continuously withdrawing treated oil from said receptacle. 35

HENRY J. BRODERSON.
